ELECTRIC DRIVE FOR LOOMS, WEAVING
MACHINES, AND THE LIKE

Fernand Phily, Lyon, France

Application July 13, 1933, Serial No. 680,321
In Germany July 18, 1932

6 Claims. (Cl. 172—239)

In looms, weaving machines and other machines of a similar nature, it is desirable, or even necessary, for the machine to stop in a certain position when brought to a standstill. In looms, for instance, the sley should be in its final position next the fabric when the loom is stopped, as it is only when the sley is in this position that incidental adjustments such as knotting threads can be performed conveniently. In many cases, a certain position is desirable for re-starting the machine. It is preferable, for instance, that, when a loom is started, the crankshaft shall make a full rotation before the first shot takes place, so that the driving motor has attained its working speed for this first shot, which then has the necessary force. Up till now, the machine, after being stopped, was brought into the desired position by hand.

The object of the present invention is an electric drive for looms, weaving machines etc., which, when switched off, automatically causes the rotor of the machine to be brought into the desired position. In accordance with the present invention, when the driving motor is switched off, after having been running in its normal direction of rotation, it is automatically switched on again for a short space of time, but in the reverse direction of rotation. When the rotor of the machine reaches the desired position, the driving motor is automatically switched off finally. For switching on the driving motor, solenoid switches are used, which can be locked with respect to each other either mechanically or electrically. The solenoid control current for the reverse rotation is under the control of a switch, the actuation of which is dependent on the position of the rotor of the machine and is effected by means of a disc provided with a suitable curve or cam, the said disc being connected to the crankshaft or a similar part of the machine.

The illustrations show examples of the realization of the invention. Fig. 1 is a drive control system in accordance with the present invention, while Figures 2, 3 and 4 show various forms of the return-movement control.

In Fig. 1, 1 is the loom driving motor, 2 and 3 are the solenoid switches for switching on the motor and 4a, 4b, 4c, are the mains supplying three-phase current. The solenoid operated switches 2 and 3 are electrically interlocked with respect to each other by means of the contacts 5 and 6. The switch 2 is also provided with a retaining or holding contact 7.

The push-button switches 8 and 9 are for switching the drive on and off. The control cur-

rent for the solenoid operated switch 3 is led over the contacts of a loom shaft operated switch 10 actuated by a disc or cam 11 provided with a suitable control-curve: The said disc 11, which is fixed to the crankshaft of the loom which is driven by the motor, is provided with a curved recess 12.

An electromagnetically operated switch 16 provided with actuating windings 17 having terminals 18 and 19, has its contacts connected in series between one terminal of the power supply and one terminal of the stop button 9. The electromagnetically actuated solenoid main line switch 2 is operated by the actuating winding 20, and the similar reversing line switch 3 is actuated by the actuating winding 21. The shaft on which cam 11 is carried is connected to motor 1 by a suitable gear train 28, 29. The switch 10 is normally held in an open position by spring 51, except when the engaging end 52 of the switch rod is forced by the contour of the cam to close the contacts of switch 10. One terminal of stop button 9 is connected by wire 32 through the contacts of switch 17 to one terminal 4b of the power supply. The other terminal of stop button 9 is connected to one terminal of start button 8, and also by wire 33 to one contact of holding switch 7. The other terminal of start switch 8 is connected by wire 34 to the other terminal of holding switch 7, and also to one terminal of actuating winding 20 of main switch 2. One contact of interlocking switch 5 actuated by winding 20 of switch 2, is connected to one terminal 4a of the power supply. The other contact of interlocking switch 5 is connected by wire 48 to one terminal of actuating winding 21 of reversing switch 3. The other terminal of actuating winding 21 is connected by wire 50 to one contact of shaft operated switch 10, and the other contact of switch 10 is connected by wire 45 to one terminal 4b of the power supply. The terminals of reversing switch 3 are respectively connected by wires 36, 37, 38, to the terminals of the power supply, and the motor terminals of the switch 3 are connected to the motor respectively by wires 39, 40, 41, through the leads 42, 43, 44, from the motor to the back contacts of the main line switch 2.

The second interlocking switch 6 is actuatable by the actuating winding 21 of the reversing switch 3, and has one contact connected by wire 46 to terminal 4a of the power supply, and has its outer contact connected by wire 49 to one terminal of actuating winding 20 of line switch 2. In Fig. 1, main line switch 2 is shown with

its contacts open, and start button 8 is open, the contacts of holding switch 7 are open, and the contacts of the interlocking switch 5 are closed. The contacts of reversing switch 3 are also open, 5 and the contacts of the second interlocking switch 6 actuatable with switch 3, are closed. If actuating winding 20 closes main switch 2, it at the same time opens the contacts of interlocking switch 5 and opens the circuit of actuating 10 winding 21 of reversing switch 3. If actuating winding 21 of reversing switch 3 closes the main contacts of switch 3, it at the same time opens the contacts of second interlocking switch 6 which in turn opens the circuit of actuating 15 winding 20 of main line switch 2. It will therefore be obvious that it is impossible for the actuating windings to close both switch 2 and switch 3 at the same time.

The terminals 18 and 19 of the electromagnetic 20 switch 16 may be connected to some suitable electrical means actuated by operation of the machine which the motor drives and actuatable when some condition occurs requiring immediate stopping of the machine, as for example in 25 a loom by breaking of the weft yarn feed.

In the operation of the arrangement shown in Fig. 1, the motor is in the condition of rest as shown in Fig. 1, and the contacts of start button 8 are open and the contacts of stop button 9 are closed, and both main line switch 2 and the reversing switch 3 are open. The cam 11 is in the position corresponding to the desired angular position of the motor shaft. The contacts of the weft yarn feed controlled switch 16 are closed. 30 When start button 8 is pressed, current is supplied from supply terminal 4b through wires 35 and 32, through buttons 9 and 8 and wire 34 to one terminal of the actuating winding 20 of main line switch 2. Since the contacts of the second interlocking switch 6 are closed, the other terminal of actuating winding 20 of main switch 2 is connected through wires 49 and 46 to terminal 4a of the power supply. The plunger of solenoid winding 20 is actuated, and the main line switch 2 is closed, at the same time opening the contacts of first interlocking switch 5, and closing the contacts of holding switch 7. Since the contacts of holding switch 7 are connected across the contacts of starting button 8, the actuating circuit closed by start button 8 is kept closed after start button 8 is released. When main line switch 2 closes, current is supplied from the power supply 4 through leads 42, 43, 44 to the terminals of motor 1, to cause it 45 to drive the loom in the normal forward direction.

When the motor is to be stopped, stop button 9 is pressed which opens the circuit from power supply terminal 4b to actuating winding 20 of main line switch 2, and switch 2 opens. At the same time, holding switch 7 opens, and first interlocking switch 5 closes. The motor shaft will normally stop in some position other than that corresponding to the desired rest position which corresponds to the recess 12 in cam 11. End 52 of the rod of switch 10 will therefore be forced by the cam periphery to close the contacts of switch 10. The circuit will be closed from supply terminal 4a through first interlocking switch 5, wire 48, actuating winding 21 of reversing switch 3, wire 50, switch 10 and wire 45 to supply terminal 4b. Reversing switch 3 will close and power will be supplied through its front connections 36, 37, 38, and its back connections 39, 70 40, 41, to motor terminals 42, 43, 44, in such a

way that motor 1 will be driven in the reverse direction until such time as the motor shaft assumes the desired position corresponding to the recess 12 in the cam 11, whereupon switch 10 will open and reversing switch 3 will be open. The reverse movement of the motor shaft is thus automatically provided for. When the contacts of switch 10 are open after reverse rotation of the motor due to the recess in cam 11 assuming the desired position, the motor is finally brought to rest. In order to prevent the loom from making any further movement after the driving motor has been disconnected, a mechanical brake can also be provided, the magnet of which is preferably connected in parallel with the field 15 winding of the motor.

By employing the present invention, the loom or other machine is automatically brought back into the desired rest position every time the main operating solenoid switch 2 is disconnected. It 20 is immaterial whether the disconnecting of switch 2 is caused by manual operation of stop button 9, or by other interruption of the power supply of actuating winding 20, by other switches, as by opening of the contacts of switch 25 16 actuatable by the weft yarn feed. One disadvantage of the arrangement shown in Fig. 1 is that with every revolution of the crank shaft of the motor, the end 52 of the rod of switch 10 is forced back and forth by the contour of cam 11, 30 which causes rapid wear of the contacts of switch 10.

Fig. 2 shows an arrangement which is more advantageous in respect to avoiding such continuous wear on the elements of switch 10. In 35 the arrangement of Fig. 2, the rod or switch 10 is held in its off position and out of frictional engagement with the cam contour during the normal running of the loom or other machine. This is accomplished by means of the solenoid 40 13 whose actuating winding is connected in series by wires 47 and 56 with one terminal of second interlocking switch 6 and one terminal of actuating winding 20 of main line switch 2. Therefore, whenever current flows through actuating 45 winding 20 to close switch 2 and operate the motor, current is also supplied through the winding of solenoid 13 and the plunger rod of switch 53 is held out of contact with the periphery of cam 23. In the arrangement shown in 50 Fig. 2, it will be desirable to give the cam a different contour than in the arrangement of Fig. 1, and the contour as shown in Fig. 2 is desirable for this purpose.

The spring 54 holds the switch 53 normally 55 closed, unless the actuating circuit of solenoid 13 is closed, or the shoulder 22 on cam 23 is in the desired position to force the actuating rod of switch 53 to open the switch. The operation of the arrangement shown in Fig. 2 is substantially the same as that of the arrangement of Fig. 1, including the paths of the currents which traverse the different circuits and elements, as heretofore explained for Fig. 1. The only essential difference is, as stated, in the arrangement 60 of Fig. 2, the end 55 of the rod of switch 53 is held out of engagement with the cam contour whenever the motor is running forward normally. The actuating circuit of winding 20 is closed through solenoid 13 instead of being connected direct to one terminal of second interlocking switch 6 as in Fig. 1. In the arrangement of Fig. 2 also, whenever main line switch 2 opens, switch 53 is closed unless the motor happens to stop in the desired position correspond- 70 75

ing to the shoulder on cam 23, and reversing switch 3 will close until the motor is brought into the desired position with the shoulder on cam 23 engaging the end 55 of the rod of switch 53.

Referring to Figs. 3 and 4, in some cases it is essential to prevent the loom or machine from continuing to run in the normal direction forward and thus take up an undesired or forbidden position after the main line switch 2 has been opened. In such cases, a pawl 14 (Fig. 3) can be provided, together with a cam 25 of suitable shape provided with the abrupt sided shoulder 24. Provision is made for releasing pawl 14 into engagement with the shoulder of cam 25 by means of the solenoid 13 connected in series to the actuating winding 20 of main line switch 2, by opening the circuit of solenoid 13 whenever the actuating circuit of switch 2 is open. Therefore when switch 2 is open, the pawl 14 drops and prevents the loom from continuing to run and take up an undesired position. In this case, it is advantageous to provide some suitable type of resilient stopping means for absorbing the shock when the machine is stopped suddenly. As shown in Fig. 3, the pawl 14 can at the same time constitute the means for contacting the cam contour and closing and opening the contacts of switch 51, instead of the end 55 of the switch rod as shown in Fig. 2.

Figs. 3 and 4 are modifications of the stopping and reverse drive control arrangement as shown in Fig. 2, and the elements and wiring shown in Figs. 3 and 4 are substitutes for the corresponding elements shown in the lower right corner of Fig. 2 connected to wires 45, 47, 50, 56.

Referring to Fig. 4, a machine may have a desired and a forbidden position which it may assume when the drive is shut off. It may also occur that these two positions are very close to each other. In a loom, for instance, the desired position is with the sley turned away from the fabric, while the sley must under no circumstances assume the beating-up position when the shuttle has not yet reached the opposite shuttle box and the drive is automatically shut off by means of the weft stop motion etc. In such cases, the cam has the shape to be seen in the example shown in Fig. 4, as cam 27. In this case, a brake action by reversing the current and the reverse motion of the rotor of the machine only take place when the pawl 14 engages in the recess 15 of the disc 27, when the switch 2 is switched off. If the machine is in another position, when the drive is switched off, the reverse current is not switched on, but the machine's momentum causes it to continue running until the rotor reaches the desired position.

The use of my invention is in no wise limited to looms and weaving machines. It can also be used for other machines, which have "desired" or "undesired" positions. It is also possible to have any particular one of these "desired" or "undesired" positions, for example, by giving the disc or cam a suitable shape.

Having now particularly described and ascertained the nature of my invention and the manner in which it is to be performed, what I claim is:

1. In an electric rotary drive system, a source of electric power, a reversible electric motor, an electrically actuatable main line switch connected for connecting said source to said motor in such manner as to cause forward rotation of said motor, an electrically actuatable reversing switch connected for connecting said source to said motor in such manner as to cause reverse rotation of said motor, interlocking means respectively

actuatable by the closing of said main switch and said reversing switch and connected respectively to the actuating circuits of said main switch and said reversing switch in such manner that only one of said switches can close at one time, and shaft-operated electric switch means connected in the actuating circuit of said reversing switch and actuatable by rotation of the shaft of said motor in such manner that the actuating circuit of said reversing switch is open only when said shaft occupies a particular determined angular position and is closed in all other positions of said shaft.

2. In an electric rotary drive system, a source of electric power, a reversible electric motor, an electrically actuatable main line switch connected for connecting said source to said motor in such manner as to cause forward rotation of said motor, an electrically actuatable reversing switch connected for connecting said source to said motor in such manner as to cause reverse rotation of said motor, interlocking means respectively actuatable by the closing of said main switch and said reversing switch and connected respectively to the actuating circuits of said main switch and said reversing switch in such manner that only one of said switches can close at one time, shaft-operated electric switch means connected in the actuating circuit of said reversing switch and actuatable by rotation of the shaft of said motor in such manner that the actuating circuit of said reversing switch is open only when said shaft occupies a particular determined angular position and is closed in all other positions of said shaft, and electrical means actuatable by the closing of the actuating circuit of said main switch for holding said shaft operating means in a frictionless position with reference to rotation of said shaft.

3. In an electric rotary drive system, a source of electric power, a reversible electric motor, an electrically actuatable main line switch connected for connecting said source to said motor in such manner as to cause forward rotation of said motor, an electrically actuatable reversing switch connected for connecting said source to said motor in such manner as to cause reverse rotation of said motor, a first interlocking switch actuatable into the closed position when said main switch is open, a second interlocking switch actuatable into the closed position when said reversing switch is open, the contacts of said first interlocking switch being connected between one terminal of said source and one terminal of the actuating winding of said reversing switch, the contacts of said second interlocking switch being connected between said terminal of said source and one terminal of the actuating winding of said main switch, a starting switch connected between the other terminal of said actuating winding of said main switch and a second terminal of said source, and a shaft-operated switch having its contacts respectively connected to said second terminal of said source and the other terminal of the actuating winding of said reversing switch, said shaft-operated switch being actuatable by rotation of the shaft of said motor in such manner that said switch is open only when said shaft occupies a particular determined angular position, and is closed in all other positions of said shaft.

4. In an electric rotary drive system, a source of electric power, a reversible electric motor, an electrically actuatable main line switch connected for connecting said source to said motor in

- such manner as to cause forward rotation of said motor, an electrically actuatable reversing switch connected for connecting said source to said motor in such manner as to cause reverse rotation 5 of said motor, interlocking means respectively actuatable by the closing of said main switch and said reversing switch and connected respectively to the actuating circuits of said main switch and said reversing switch in such manner that only 10 one of said switches can close at one time, a cam carried by the shaft, of said motor, and cam-operated electric switch means connected in the actuating circuit of said reversing switch and actuatable by said cam, said cam being so shaped 15 that said cam-operated switch means is actuated into the open position only when said shaft occupies a particular determined position, and is closed for all other positions of said shaft.
5. In an electric rotary drive system, a source 20 of electric power, a reversible electric motor, an electrically actuatable main line switch connected for connecting said source to said motor in such manner as to cause forward rotation of said motor, an electrically actuatable reversing switch 25 connected for connecting said source to said motor in such manner as to cause reverse rotation of said motor, interlocking means respectively actuatable by the closing of said main switch and said reversing switch and connected respectively to the actuating circuits of said main switch 30 and said reversing switch in such manner that only one of said switches can close at one time, a cam carried by the shaft of said motor and being provided with a projecting shoulder abrupt on one side and sloping gradually on the other side, a pawl mounted to engage said abrupt side of said shoulder, electrical means for controlling the release of said pawl into engaging position and connected for holding said pawl out of engagement with said shoulder when the actuating circuit of said main switch is closed, and electrical switch means actuatable into the closed position by said pawl when released, said last mentioned switch means being connected for closing the actuating circuit of said reversing switch. 35

that said cam-operated switch means is actuated into the open position only when said shaft occupies a particular determined position, and is closed for all other positions of said shaft, and electrical means actuatable by the closing of the actuating circuit of said main switch for holding said cam-operated means out of engagement with said cam when said main switch is closed.

6. In an electric rotary drive system, a source of electric power, a reversible electric motor, an electrically actuatable main line switch connected for connecting said source to said motor in such manner as to cause forward rotation of said motor, an electrically actuatable reversing switch connected for connecting said source to said motor in such manner as to cause reverse rotation of said motor, interlocking means respectively actuatable by the closing of said main switch and said reversing switch and connected respectively to the actuating circuits of said main switch and said reversing switch in such manner that only one of said switches can close at one time, a cam carried by the shaft of said motor and being provided with a projecting shoulder abrupt on one side and sloping gradually on the other side, a pawl mounted to engage said abrupt side of said shoulder, electrical means for controlling the release of said pawl into engaging position and connected for holding said pawl out of engagement with said shoulder when the actuating circuit of said main switch is closed, and electrical switch means actuatable into the closed position by said pawl when released, said last mentioned switch means being connected for closing the actuating circuit of said reversing switch. 35

FERNAND PHILY. 35
